UNITED STATES PATENT OFFICE

153,012

DESIGN FOR AN INTEROFFICE COMMUNICATION CABINET OR SIMILAR ARTICLE

Joseph Palma, Jr., Berwyn, Ill., assignor to The Rauland Corporation, Chicago, Ill., a corporation of Illinois

Application October 20, 1947, Serial No. 142,038

Term of patent 14 years

(Cl. D26—14)

To all whom it may concern:

Be it known that I, Joseph Palma, Jr., a citizen of the United States, residing at Berwyn, in the county of Cook and State of Illinois, have invented a new, original, and ornamental Design for an Interoffice Communication Cabinet or Similar Article, of which the following is a specification, reference being had to the accompanying drawing, forming part thereof.

The figure is a perspective view of an interoffice communication cabinet or similar article, showing my new design.

I claim:

The ornamental design for an interoffice communication cabinet or similar article, as shown.

JOSEPH PALMA, JR.
